UNITED STATES PATENT OFFICE

EDWARD R. MROSS AND EMANUEL NIELSEN, OF RACINE, WISCONSIN, ASSIGNOR TO
HAMILTON BEACH MFG. CO., OF RACINE, WISCONSIN, A CORPORATION OF WISCONSIN

MOTOR CONTROLLER

Application filed March 19, 1928. Serial No. 262,798.

This invention relates to motor controllers adapted more particularly for controlling motors applied to sewing machines, although obviously it may be used to control motors of other light machinery.

One of the objects of the invention is to produce an exceedingly compact device, which may be used to rest upon the floor and be foot operated and which, with very slight modification, will be suitable for attachment to a sewing machine cabinet and be knee operated.

Another object of the invention is to provide a movable contact arm, for engaging the fixed contacts of the resistance unit, which shall be pivotally mounted in the controller housing and be located within the housing, instead of being carried by the treadle plate which is necessarily exterior to the controller housing.

Our invention is shown as embodied in combination with a resistance unit of the type shown and described in United States Letters Patent No. 1,644,820, dated October 11, 1927. By the construction about to be described and claimed herein, the controller is materially reduced in size, is made very dependable in operation, is strong and durable and readily interchangeable as a foot or knee operated controller.

In that embodiment of our invention shown in the drawings:

Figure 1 is a perspective view of the invention as embodied in a foot operated motor controller.

Figure 2 is a top plan view of the same with the upper housing plate removed.

Figure 3 is a side elevation of the device shown in Figure 1.

Figure 4 is a transverse, vertical sectional view, taken in the plane of the line 4—4 of Figure 3, looking in the direction indicated by the arrows.

Figure 5 is a bottom view of the movable contact arm and bracket by which it is mounted in the controller housing.

Figure 6 is a transverse, vertical sectional view taken in the plane of the line 6—6 of Figure 7, looking in the direction indicated by the arrows.

Figure 7 is a perspective view of the movable contact arm and bracket by which it is mounted in the housing.

Figure 8 is a vertical, sectional view taken in the plane of the line 8—8 of Figure 9.

Figure 9 shows the controller of Figure 1 so modified as to be adapted for connection to a cabinet and to be knee controlled.

Referring more particularly to Figures 1 to 4, inclusive, the controller housing comprises a metallic base plate 10, upturned, longitudinal side walls 11 and 12 integral with the base, and an apertured cover plate 13 which forms the top and two end walls of the housing. The latter is connected to the base plate 10 by clips 14 which extend through slots 15. One end of the plate 13 is apertured, as indicated at 16, to accommodate the current wires 17. The side wall 12 is cut away, as indicated at 18 in Figures 1 and 3, for a purpose hereinafter referred to. The lower surface of the base member 10 is provided with a pair of flat straps 19 to which rubber feet 20 are attached.

Within the housing is a resistance unit of the type shown in Patent No. 1,644,820 aforementioned, which will be briefly described as follows: A bracket 21 is secured by screws 22 to the side wall 12 and to an insulating block 23 to hold the latter in proper position in the controller housing. The block 23 is grooved to receive the resistance wire 24 wound thereon. One end of the resistance wire 24, near the side wall 11, is in contact with a stud 25 fixed in the block 23. Similar contact studs 26, arranged in alignment in the block 23, engage the resistance wire convolutions. An elongated contact member 27, spaced from the resistance wire 24 and also spaced from the studs 25, 26, is mounted on the block 23 to be substantially parallel to the line of studs 25 and 26.

To support a movable contact arm which is about to be described, when it is in inoperative position, the block 23 is provided with a pair of insulated studs 28, in the same horizontal plane as the studs 25 and 26. One end of the resistance wire 24 is connected to a post 29 and one end of the fixed contact 27 is connected to a post 30; said posts 29

and 30 being connected in an electrical circuit through the wires 17.

The movable contact arm by which the electrical circuit may be completed, and by which the resistance may be cut out of the circuit to a desired extent, comprises a yielding arm 31, provided at one end with a movable contact member 32. The contact member 32 is slotted to receive the downturned end of the arm 31. This construction insures intimate electrical contact between the contact member 32 and the fixed contacts 27 and 25, 26. The contact member 32 is angular or offset in contour so that in moving sidewise to open the circuit, the portion nearest the end of the arm 31 will disengage one end of the fixed contact 27 and open the circuit before the extreme end portion of the member 32 disengages the fixed contact 25. By this construction arcing is practically eliminated.

The means for mounting the movable contact arm 31 in the controller housing will now be described: As shown in Figures 5, 6 and 7, the flat end 33 of the arm 31 is rigidly secured to a metal bracket which is insulated therefrom by an insulating block 34. The block 34 is recessed in both its upper and lower surfaces, as indicated at 35, to prevent the ends of the rivets 36, by which the arm 31 is connected to the block, from contacting with the metal bracket, and to prevent the ends of the rivets 37, by which the bracket is connected to the block, from contacting with the metal of the end 33 of the arm 31.

The bracket to which the block 34 is connected comprises two horizontally disposed members 38, 39, integral with a vertically arranged member 40 having an angular extension 41 at one side. The upper horizontal member is elongated to provide means for attachment to the block 34 and to firmly support the spring arm 31. Each of the members 38, 39, is provided with an aperture 42 to receive the pivot pin 43, one end of which is secured in the base 10 and the other end in the inturned ear 44 which is formed of part of the metal cut away at 18 from the side wall 12, the ear 44 being integral with the side wall 12.

The bracket member 38 is apertured, inwardly of its pivotal connection 43, to receive one end of the coiled spring 45, the other end of which is connected to a struck out loop 46 on the side of the casing wall 11. The spring 45 functions to normally hold the bracket and movable contact arm in the position shown in Figure 2, with the contact member 32 out of contact with the fixed contact points of the resistance unit.

The arrangement shown and described is such that the resistance unit, movable contact arm, and the means for mounting same firmly but movably, are all located entirely within the controller housing, the only exposed portion being the extension 41 of the

bracket by means of which the bracket and connected contact arm are moved against the tension of the spring 45 in the manner about to be explained.

Mounted on top of the casing member 13 is a treadle plate 47 which is substantially flat and provided with downwardly extending arms 48 and 49 which are substantially at right angles to the foot plate 47 and fit against the housing sides 11 and 12, respectively. Extending horizontally through the arm 48, casing sides 11, 12, and flange 49 is a screw threaded sleeve 50 held in position by screws 50', said sleeve 50 forming a pivotal connection between the arms of the treadle plate 47 and the controller housing. The arm 49 is longer than the other flange 48, and extends downwardly so as to be opposite the cut away portion 18 of the wall 12. It has a pair of inturned flanges 51 at its lower end, best shown in Figures 1 and 3, one of which engages the edge of the cut away wall 12 and the other contacts with the extension 41 of the bracket member when the treadle plate 47 is in normal position. The parts are held in said position by the tension of the spring 45 which causes the extension 41 of the bracket to bear against the end 51 of the arm 49, maintaining the treadle 47 in raised position. When pressure is brought to bear upon the treadle plate 47 by the foot of the operator, one inturned portion 51 of the arm 49, through the casing opening 18, engages the extension 41 on the bracket member 40, causing the bracket to move about its pivot 43, the horizontal member 38 carrying the yielding contact arm 31 across the fixed contacts against the tension of the spring 45, whereby the resistance is cut out to any desired extent. As soon as pressure on the plate 47 is released the parts return to normal position or out of contact position.

It will be noted that only a very slight movement of the foot plate 47 is required in order to move the contact member 32 on the end of the arm 31 across the fixed contacts of the resistance unit. This is accomplished through the construction and arrangement of the contact arm bracket and the plate 47 and its arm 49. The plane of movement of the contact arm is substantially at right angles to the plane in which the operating plate is moved.

Referring now to Figures 8 and 9, which show a knee operated controller, it will be noted that the parts of the controller housing corresponding to the parts just described have been similarly designated. The interior construction is identical with that of the foot operated controller. In place of the feet 20, heretofore described, the base of the knee control is provided with flat metal straps 51' apertured for attachment to the vertical side wall of the sewing machine cabinet adjacent to the knee of the user. To the free end of

the plate 47 is attached a knee control lever comprising a curved portion 52 and flat portion 53. The flat portion 53 is apertured and connected to the treadle plate 47 by a headed bolt 54 and nut 55. A sleeve 56 surrounds the bolt 54 and between the plate 47 and the nut 55 is a dished spring washer 57. Instead of a dished spring washer, a coiled spring may be used between the plate 47 and nut 55, such spring surrounding the bolt 54 or sleeve 56, to form tension means. The plate 47 is preferably roughened or ribbed as indicated in Figure 8.

By the construction shown and described, the knee control lever 52, 53, is movably mounted on the treadle plate 57 and has such frictional engagement therewith that it will remain in any desired predetermined position. When in use it is preferably turned downwardly as shown in full lines in Figure 9, and when not in use it may be moved to the position shown in dotted lines in said figure, where it will be out of sight. If the device, having the treadle plate 47 and the adjustable lever 52, 53, is to be placed on the floor for foot operation, the upwardly curved portion 52 is moved around to a position to overlie the treadle plate as shown in dotted lines in Fig. 9. In this position the curved lever functions as a clip or stop to overlie and engage the toe of the operator's shoe while resting on the treadle plate and thereby cooperates with the treadle plate, insuring more positive and accurate operation of the controller.

Obviously changes in details of construction may be made without departing from our invention. For example, the offset portion 32 of the contact arm 31 may be arranged to disengage the fixed contacts before disengaging the elongated contact 27 in moving to inoperative position.

We claim as our invention:

1. A portable motor controller comprising a housing, an insulating block in the housing, a resistance carried by the block, fixed contacts associated with the block, an elongated movable arm having a contact member at one end for engagement with the fixed contacts, a bracket pivotally mounted in the housing, the end of the movable arm opposite the contact member end being secured on said bracket, means for normally holding the contact arm in inoperative position, a treadle plate pivotally mounted on the housing and means for causing said elongated arm to move across said fixed contacts by a slight movement of the treadle plate, said means comprising an arm extending downwardly from the treadle plate exterior of said housing and having a cam face entering the housing in engagement with the bracket to move the latter about its pivotal mounting in the housing when the treadle plate is depressed.

2. A motor controller comprising a hous-

ing, an insulating block in the housing, a resistance carried by the block, fixed contacts associated with the block, a movable contact arm adapted at one end for engagement with the fixed contacts, a bracket pivotally mounted in the housing and rigidly connected to the other end of said contact arm, said bracket having an outwardly directed extension protruding through an opening in the housing, tension means between the bracket and housing for normally holding the contact arm in inoperative position, and a treadle plate pivotally mounted externally of the housing and having a cam arm extending downwardly therefrom adjacent one side of the housing adapted to engage said protruding part of the bracket to move the bracket about its pivotal connection in the housing when the plate is depressed.

3. A motor controller comprising a housing having one of its side walls cut and bent to form an opening therein and an ear extending inwardly from said wall, an insulating block in the housing, a resistance carried by the block, fixed contacts associated with the block, a movable contact arm adapted for engagement at one end with the fixed contacts, a bracket rigidly connected to the other end of the movable contact arm and pivotally mounted between the housing base and said inwardly extending ear, said bracket having a perpendicular lateral extension protruding through the housing opening, tension means for normally holding the movable arm in inoperative position, and a treadle plate pivotally mounted externally of the housing and having a downwardly extending cam arm at the side of the housing in engagement with said protruding extension, adapted to move the bracket about its pivotal connection in the housing when the treadle plate is depressed by the operator.

4. A portable motor controller attachment for sewing machines, adapted to be pressure operated, comprising a housing, an insulating block in the housing a resistance carried by the block, fixed contacts associated with the block, an elongated movable arm having a contact member at one end for engagement with the fixed contacts, a bracket pivotally mounted in the housing, the end of the movable arm opposite the contact member end being secured on said bracket, means for normally holding the contact arm in inoperative position, treadle plate pivotally mounted on the housing and means for causing said elongated arm to move across said fixed contacts by a slight movement of the treadle plate, said means comprising a cam arm extending downwardly from the treadle plate near its pivoted end and in engagement with the bracket to move the latter about its pivotal mounting in the housing when the treadle plate is depressed, and a lever adapted to be

knee-operated, the lever connected at one end to the free end of the treadle plate.

5. A portable motor controller attachment for sewing machines, adapted to be pressure operated, comprising a housing, an insulating block in the housing a resistance carried by the block, fixed contacts associated with one block, an elongated movable arm having a contact member at one end for engagement with the fixed contacts, a bracket pivotally mounted in the housing, the end of the movable arm opposite the contact member end being secured on said bracket, means for normally holding the contact arm in in-operative position, a treadle plate pivotally mounted on the housing and cam means for causing said elongated arm to move across said fixed contacts by a slight movement of the treadle plate, said means comprising an arm extending downwardly from the treadle plate near its pivoted end and in engagement with the bracket to move the latter about its pivotal mounting in the housing when the treadle plate is depressed, and a curved lever adapted to be knee-operated, movably connected at one end to the free end of the treadle plate, the free end of the knee-operated lever being spaced from the treadle plate when said lever and plate are in superposed position.
- 30 6. A rheostat comprising, a housing, a resistance element within said housing, a bracket pivotally mounted within said housing having a perpendicularly extending lateral extension, a swinging contact arm secured on said bracket, means for holding said bracket and contact arm normally in inoperative position, and an operating member pivoted on said housing and having a cam element engaging the lateral extension of said bracket.
- 35 7. A rheostat comprising a housing, a resistance element within said housing, a bracket pivotally mounted within said housing having a lateral extension, a swinging contact arm secured on said bracket, means for holding said bracket and contact arm normally in inoperative position, a lever pivoted at one end on said housing and having an arm extending downwardly adjacent its pivoted end into engagement with the lateral extension on the bracket, and a curved lever pivotally connected to the free end of the first mentioned lever, said curved lever being spaced from the pivotal lever when they are in superposed relation.
- 40 8. In testimony, that we claim the foregoing as our invention we affix our signatures this 13th day of March, 1928.

EDWARD R. MROSS.
EMANUEL NIELSEN.
